DESIGN FOR A DOG BLANKET

Anne Ardmore, North Hollywood, Calif.

Application July 24, 1945, Serial No. 120,937

Term of patent 7 years

(Cl. D38—10)

To all whom it may concern:

Be it known that I, Anne Ardmore, a citizen of the United States, residing at North Hollywood, in the county of Los Angeles and State of California, have invented a new, original, and ornamental Design for a Dog Blanket, of which the following is a specification, reference being had to the accompanying drawing, forming part thereof.

Fig. 1 is a side perspective view of a dog blanket showing my new design;

Fig. 2 is a top plan view.

Fig. 3 is a front elevational view thereof.

I claim:

The ornamental design for a dog blanket, as shown.

ANNE ARDMORE.
